(57) CLAIM

The ornamental design for a first aid kit, as shown and described.

DESCRIPTION

The patent or application file contains at least one drawing executed in color. Copies of this patent or patent application publication with color drawing(s) will be provided by the Office upon request and payment of the necessary fee.

FIG. 1 is an upper rear right side perspective view of a first aid kit showing the new design, in accordance with a first embodiment.

FIG. 2 is a rear elevation view of the first aid kit shown in FIG. 1.

FIG. 3 is a front elevation view of the first aid kit shown in FIG. 1.

FIG. 4 is a left side elevation view of the first aid kit shown in FIG. 1.

FIG. 5 is a right side elevation view of the first aid kit shown in FIG. 1.

FIG. 6 is a top view of the first aid kit shown in FIG. 1.

FIG. 7 is a bottom view of the first aid kit shown in FIG. 1.

FIG. 8 is an internal view of the first aid kit shown in FIG. 1.

FIG. 9 is an upper rear right side perspective view of the first aid kit shown in FIG. 1 with hook and loop omitted, in accordance with a second embodiment.

FIG. 10 is a rear elevation view of the first aid kit shown in FIG. 9.

FIG. 11 is a front elevation view of the first aid kit shown in FIG. 9.

FIG. 12 is a left side elevation view of the first aid kit shown in FIG. 9.

FIG. 13 is a right side elevation view of the first aid kit shown in FIG. 9.

FIG. 14 is a top view of the first aid kit shown in FIG. 9.

FIG. 15 is a bottom view of the first aid kit shown in FIG. 9; and,

FIG. 16 is an internal view of the first aid kit shown in FIG. 9.

The broken lines of the drawing represent stitching that forms no part of the claimed design. The crosshatch shading represents hook and loop fastener which forms no part of the claimed design.
